UNITED STATES PATENT OFFICE.

MAURICE L. WILLARD, OF CHICAGO, ILLINOIS, ASSIGNOR TO THE SUPERIOR TYPE COMPANY, OF CHICAGO, ILLINOIS, A CORPORATION OF ILLINOIS.

INKING-PAD.

1,251,721.

Specification of Letters Patent.

Patented Jan. 1, 1918.

Application filed April 11, 1916. Serial No. 90,425.

To all whom it may concern:

Be it known that I, MAURICE L. WILLARD, a citizen of the United States, and a resident of Chicago, in the county of Cook and State 5 of Illinois, have invented certain new and useful Improvements in Inking-Pads, of which the following is a specification.

This invention relates to improvements in inking pads for hand stamps and the object 10 of the invention is to provide a pad which will be neat in appearance, durable in use, and one which will not scratch the surface of the most highly polished desk.

The invention in its preferable embodiment, consists of the construction and arrangement herein described and then definitely claimed.

In the drawings accompanying and forming part hereof:

20 Figure 1 is a perspective view of my pad.

Fig. 2 is a top plan view, with the cover thrown open and with parts broken away.

Fig. 3 is a vertical transverse section.

Referring now to the details of the drawings by numerals: 1 designates the base which is preferably formed of vulcanized rubber and is provided with a thin piece of sheet metal 2 vulcanized therein as clearly indicated in Fig. 3 so that the pad will have 25 the desired stiffness or firmness. The base is provided with side and end walls 4 which extend entirely around the same and leave a recess for the insertion of a pad 6. At opposite ends of the rear of the base 1 are two 30 lugs 8 and 10 which are perforated as shown at 11 for the reception of a pintle 12 which passes through cylindrical members 14 of a cover 15 and into the perforations 11, thereby forming a hinge and permitting the cover 35 to be swung from the closed position indicated in Fig. 1 to the open position shown in Fig. 2.

The pad itself is formed of any desirable ink holding material 18 placed upon a stiff 40 and preferably metal plate 20 of proper size to fit in the recess left between the side and end walls 4, the covering of the pad, which extends over the ink holding material 18, being turned under the metal plate 20 and 45 secured thereto in any desirable way.

In the act of assembling the pad it will be obvious that the pad may be placed in the recess between the walls 4, and may be cemented therein or not as desired. The cover 50

may be easily secured in position after the 55 pintle has been placed through the members 14 by bending the lugs 8 and 10 as shown in Fig. 2, the lugs springing back into position as soon as released.

From the foregoing and accompanying 60 drawings it will be seen that I have provided a pad which, while formed of relatively soft vulcanized rubber, has all the stiffness of a metal frame, and at the same time it will not mar the highly polished surface of a desk. The frame is very durable 65 in use and neat in appearance.

I do not limit myself to the exact construction shown in the drawings but reference should be made to the appended claims to 70 determine the scope of the invention.

What I claim as my invention is:

1. In a stamp pad, a base formed of relatively soft material having a recess for the pad, and a stiff plate located in said base, 75 substantially as described.

2. In a stamp pad, a base formed of relatively soft material having a recess for the pad, lugs at the rear of the same, a cover, and a pintle projecting from said cover and 80 into said lugs, substantially as described.

3. In a stamp pad, a base formed of relatively soft material having a stiff plate located therein, side and end walls forming a recess for the pad, and a pad located in said 85 recess, substantially as described.

4. In a stamp pad, a base formed of relatively soft material, walls projecting from said base and forming a recess for the pad, lugs at the rear of the same, a cover, and a 90 pintle projecting from said cover and into said lugs, substantially as described.

5. In a stamp pad, a base formed of relatively soft material having a stiff plate 95 located therein, walls projecting from said base and forming a recess for the pad, lugs at the rear of the same, a cover, and a pintle projecting from said cover and into said lugs, substantially as described.

6. In a stamp pad, a base formed of relatively soft material having a recess or opening for the pad, and a pad located in said recess and having a stiff plate therein, substantially as described.

7. In a stamp pad, a base formed of relatively soft material having a stiff plate located therein and having an opening for a pad, and a pad located in said opening and

having a stiff plate therein, substantially as described.

8. In a stamp pad, a base formed of relatively soft material having a stiff plate located therein and having an opening for a pad, lugs at the rear of said base, a cover, a pintle projecting from said cover and into said lugs, and a pad located in said opening

and having a stiff plate therein, substantially as described. 10

In testimony whereof I affix my signature in presence of two witnesses.

MAURICE L. WILLARD.
